UNITED STATES PATENT OFFICE.

BENJAMIN F. COPP, OF LAS CRUCES, TERRITORY OF NEW MEXICO.

DENTAL INLAY-HOLDER.

939,476.

Specification of Letters Patent. Patented Nov. 9, 1909.

application filed July 2, 1909. Serial No. 505,705.

To all whom it may concern:

Be it known that I, BENJAMIN F. COPP, a citizen of the United States, residing at Las Cruces, in the county of Dona Ana and Territory of New Mexico, have invented a new and useful Dental Inlay-Holder, of which the following is a specification.

The objects of the invention are, generally, the provision, in a merchantable form, of a device of the class above mentioned, which shall be inexpensive to manufacture, facile in operation, and devoid of complicated parts; specifically, the provision of an implement adapted to hold crowns, fillings, and the like, while the same are being polished or subjected to other mechanical manipulation, the implement being so constructed that it will firmly hold the substance which is being worked, without scratching or mutilating the same; other and further objects being made manifest hereinafter, as the description of the invention progresses.

The invention consists in the novel arrangement and construction of parts herein-after described, delineated in the accompanying drawings, and particularly pointed out in that portion of this instrument wherein patentable novelty is claimed for certain peculiar and distinctive features of the device, it being understood that, within the scope of what hereinafter thus is claimed, divers changes in the form, proportions, size, and minor details of the structure may be made, without departing from the spirit or sacrificing any of the advantages of the invention.

Similar numerals of reference are employed to denote corresponding parts throughout the several figures of the drawings:—

In the accompanying drawings:—Figure 1 is a longitudinal section, parts being in elevation; Fig. 2 is an end elevation of the handle and the tube, the adhesive element being removed; and Fig. 3 is a longitudinal section of a modified form of the invention, parts being in elevation.

In carrying out my invention, I provide, primarily, a holder consisting of a handle 1, in one end of which is mounted a tube 2, arranged to project beyond the handle 1, and provided, in its projecting portion, with a

plurality of apertures 3. Mounted upon the end of the tube 2 is an adhesive member 4. This adhesive member 4 may be fashioned from wax, cement, or other like substance, adapted to hold firmly the element which is to be manipulated, the same in the present instance being shown in the form of a crown 5, provided with a pin 6.

The adhesive member 4 may be fashioned from any cement, wax, or modeling compound, and its structure may be such that it will soften upon the application of heat. When thus softened, the crown, or other element which is to be polished is inserted into the adhesive member, and the crown and the adhesive member introduced into cold water, to harden the adhesive member about the crown. After the adhesive member has thus hardened, the crown may be polished or otherwise manipulated.

The apertures 3 in the tube 2 serve to engage the adhesive member 4, and to permit the same, when heated, or otherwise softened to find its way into the interior of the tube 2, whereby the adhesive member and the tube may be rigidly assembled.

The device is, as hereinbefore pointed out, adapted to hold a variety of articles for mechanical manipulation. However, owing to the tubular form of the member 2, into which the pin 6 is adapted to move, the device is peculiarly adapted for handling pin crowns, the cement or other substance constituting the adhesive member, engaging the pin 6, and the inner walls of the member 2.

The adhesive member 4 is preferably arranged to abut against the extremity of the handle 1, about the tube 2 which is mounted therein, this abutment between the adhesive member and the handle stiffening the structure, and tending to make the same rigid after the cement has hardened.

In Fig. 3, I have shown a slight modification of the invention, the same consisting in cutting away a portion of the side wall of the tube 2, as denoted by the numeral 8. The advantages incident to this construction are that the device is thus adapted to conform to the shape of an anterior crown 7.

Having thus described my invention, what I claim as new and desire to protect, by Letters Patent is:—

1. A device of the class described comprising a tube and an adhesive member mounted upon the tube.
2. A device of the class described comprising a perforated tube and an adhesive member mounted upon the tube and arranged to engage the perforations thereof.

In testimony that I claim the foregoing as my own, I have hereto affixed my signature in the presence of two witnesses.

BENJAMIN F. COPP.
